UNITED STATES PATENT OFFICE.

PHILIP C. STRAHL, OF LAWRENCE, KANSAS, ASSIGNOR OF ONE-HALF TO
HENRY KLAAS, OF SAME PLACE.

DESIGN FOR A GRATE-BAR.

SPECIFICATION forming part of Design No. 28,985, dated July 5, 1898.

Application filed June 9, 1898. Serial No. 683,035. Term of patent 14 years.

To all whom it may concern:

Be it known that I, PHILIP C. STRAHL, a citizen of the United States, residing at Lawrence, in the county of Douglas and State of Kansas, have invented a new and original Design for a Grate-Bar, of which the following is a specification.

This invention relates to a new and original design for a grate-bar; and it has for its object to provide a design of this character that shall be both useful and ornamental.

The leading feature of the design resides in a flat rectangular plate provided therein with a plurality of circular openings with 15 separate spaced substantially rectangular slots disposed longitudinally thereof and arranged in pairs, with the slots of each pair in longitudinal alinement, and with a pair of parallel approximately **W**-shaped pendent 20 ribs extending longitudinally of the plate, at the under side thereof, and lying in the vertical plane of said slots.

The minor features of the design are the rectangular plate having the circular openings of a downwardly-flaring form and provided with squared lateral projections at the ends of its opposite longitudinal side edges, and transverse-cleat projections disposed beyond the ends of the **W**-shaped pendent ribs.

In the drawings, Figure 1 is a perspective view of a grate-bar embodying the herein-described design. Fig. 2 is a longitudinal sectional view, the plane of section including one pair of the longitudinally-alined slots.

Fig. 3 is a transverse sectional view on the line 3 3 of Fig. 2.

Referring particularly to the drawings, the numeral 1 designates a rectangular plate provided therein with a plurality of circular openings 2, which are of a downwardly-flaring form. At its opposite ends and on the under side thereof the said rectangular plate 1 is further provided with transverse-cleat projections 3, and at the ends of its longitudinal side edges with the squared lateral projections 4.

In addition to the features referred to the rectangular plate 1 is provided in the body portion thereof with separate spaced substantially rectangular slots disposed longitudinally of the plate and arranged in pairs, with the slots of each pair in longitudinal alinement. At its under side the plate 1 is also provided with a pair of approximately **W**-shaped flat pendent ribs 6. These ribs 6 extend longitudinally of the plate, from end to end thereof, and are disposed in the vertical plane of said rectangular slots, which slots, while of a general rectangular form, are rounded at their ends, as clearly illustrated in the drawings.

What is claimed is—

The design for a grate-bar herein shown and described.

In testimony that I claim the foregoing as my own I have hereto affixed my signature in the presence of two witnesses.

PHILIP C. X STRAHL.
